Primary Examiner — Natasha Vujcic*Assistant Examiner* — Gilbert B Ford(74) *Attorney, Agent, or Firm* — Kilpatrick Townsend & Stockton LLP(57) **CLAIM**

The ornamental design for an inlet suction strainer, as shown and described.

DESCRIPTION

FIG. 1 is a perspective view of an inlet suction strainer showing our new design;

FIG. 2 is a bottom plan view thereof;

FIG. 3 is a top plan view thereof;

FIG. 4 is a first side view thereof;

FIG. 5 is a second side view thereof;

FIG. 6 is a cross-sectional view taken along the lines 6-6 in FIG. 1; and,

FIG. 7 illustrates the inlet suction strainer coupled to an outlet of a bag via friction fit.

The broken lines in the drawings illustrate portions of the environment of the inlet suction strainer, which forms no part of the claimed design.

1 Claim, 7 Drawing Sheets(56)
